(57) **CLAIM**

The ornamental design for a combined ant nest with trash area and water feeder, as shown and described.

DESCRIPTION

FIG. 1 is a front perspective view of a combined ant nest with trash area and water feeder, showing my new design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the combined ant nest with trash area and water feeder that form no part of the claimed design.
